UNITED STATES PATENT OFFICE.

GEORGE GAVIN AND LAWRENCE WASHINGTON CROMER, OF EUREKA,
NEVADA.

BIT-BRACE.

SPECIFICATION forming part of Letters Patent No. 366,826, dated July 19, 1887.

Application filed July 24, 1886. Serial No. 209,021. (No model.)

To all whom it may concern:

Be it known that we, GEORGE GAVIN and LAWRENCE WASHINGTON CROMER, of Eureka, in the county of Eureka and State of Nevada, 5 have invented a new and Improved Bit-Brace, of which the following is a full, clear, and exact description.

Our invention consists in the construction and arrangement of parts, as will be herein-
10 after fully described and claimed.

Reference is to be had to the accompanying drawings, forming a part of this specification, in which similar letters of reference indicate corresponding parts in all the figures.

15 Figure 1 is a front elevation of our bit-stock as applied to a ratchet-brace, with the bit locked in position by the sliding bolt. Fig. 2 is a horizontal section thereof, and Fig. 3 a vertical transverse section of the same. Fig. 20 4 is a front elevation of our bit-stock as used with the ordinary brace.

A represents a portion of a brace, and B a bit-stock, usually made cylindrical in form and secured to the brace in the ordinary manner.

25 At the lower end, upon one side of the bit-stock B and extending through the socket thereof, is cut a T-shaped slot, C, the vertical portion of which extends through the lower edge of the bit-stock, dividing the same.

30 The socket of the bit-stock is provided with a cylindrical bore adapted to receive a similar cylindrically-shaped bit-shank, D, provided above the shoulder thereof with a pin, a, which when the bit-shank is in position within 35 the socket of the bit-stock engages either end, as desired, of the horizontal arm of the T-slot C.

A vertical groove, b, is cut in the face of the bit-stock B from a distance above the T-shaped slot C, merging into its horizontal arm opposite the vertical arm of said slot C, the width of the groove b being greater than that of the said T-shaped slot. Into the groove b thus formed a bolt, E, provided with a central slot, e, and an upper thumb-hold, e', is adapted to slide down to a position against the under side of the horizontal arm of the slot C, dividing the said arm and retaining the pin a of the bit-shank D in one of the 45 divisions thus formed, as shown in Fig. 1. The

bolt E is securely held in position by a set-screw, d, which enters the slot e therein, and is screwed down to a bearing upon the sides of the said slot into the bit-stock B. The pin a is thus held securely in either division of the 55 horizontal arm of the T-slot C, and as the bolt E forms a cap for the vertical arm of the said slot the pin a cannot enter therein until the bolt E is slid to its upward position, which is in line with the upper side of the horizontal 60 arm of the said slot C.

It is only necessary to employ the bolt E when the bit-stock is attached to a ratchet-brace. The pin a is then bolted thereby, as described, in either the right or left division 65 of the horizontal arm of the T-shaped slot C, to accommodate the desired movement of the ratchet.

The bit-stock is complete without the sliding bolt E for use with ordinary braces, as in 70 boring a hole, for instance, the pin a of the bit-shank D, which is entered through the vertical arm of the slot C, will bear against the left-hand end of the horizontal arm thereof, and as the motion of the brace is reversed to 75 withdraw the auger the pin finds its bearing against the opposite or right-hand end of the said horizontal arm of the said slot. Therefore in this connection a lock is not needed.

The construction of our bit-stock, also that 80 of the bit-shank, is most simple in every particular, and does not contain a single element liable to displacement or breakage, and together they operate in as perfect manner as any socket or bit heretofore used, while the cost 85 of construction is reduced to a minimum figure.

The operation is briefly as follows: When an ordinary brace is employed, the bit shank is mounted into the socket of the bit-stock, 90 the pin or stop a thereon passing up through the vertical arm of the T-slot C to engagement with either end of its horizontal arm, as required—for example, to drive a screw upon the left to withdraw it upon the right. When 95 employed with a ratchet-brace, the additional operation is had of sliding the bolt E down to its bearing upon the under side of the horizontal arm of the slot C, in order to lock the pin a of the bit-shank D in either the right or 100

left division of the T-shaped slot C, as the nature of the work may demand. We do not limit the application of our invention to bit-stocks and bits, as shown, as the same may be 5 otherwise applied—as, for instance, to augers and auger-handles.

Having thus described our invention, what we claim as new, and desire to secure by Letters Patent, is—

- 10 1. The combination, with the bit-stock having a vertical bit-socket, and an angular slot leading from the end of the stock and communicating with its socket, of a slotted vertically-sliding bolt adapted to slide over the vertical 15 arm of said slot to close the same and pro-

vided with a thumb or finger-piece, and a screw passing through the slot in the bolt into the stock, substantially as set forth.

2. The combination, with a bit-stock, B, of cylindrical bore, having a T-shaped opening, 20 C, cut therein, of a sliding bolt, E, having a central slot, e, embossed thumb-hold e', and set-screw d, substantially as shown and described, and for the purposes herein set forth.

GEORGE GAVIN.

LAWRENCE WASHINGTON CROMER.
